CLAIM

I claim, the ornamental design for a golf club head cover, as shown and described.

DESCRIPTION

FIG. 1 is a perspective view of a new golf club head cover design;

FIG. 2 is a top view thereof;

FIG. 3 is a bottom side view thereof;

FIG. 4 is a back side view thereof;

FIG. 5 is a front side view thereof;

FIG. 6 is a left side view thereof;

FIG. 7 is a right side view thereof;

FIG. 8 is a further perspective view thereof, showing the inside of the golf club head cover in an alternate position; and,

FIG. 9 is a bottom side view thereof, shown the outside of the golf club head cover in an alternate position.

The broken lines showing is illustrating conventional stitching. The stippling showing is illustrating texture in the golf club head cover.
